UNITED STATES PATENT OFFICE.

ANDERS HOLMBERG, OF STOCKHOLM, SWEDEN, ASSIGNOR TO HELGE GUSTAF TORULF, OF STOCKHOLM, SWEDEN.

APPARATUS FOR SINTERING FINE ORES OR PULVERULENT ORES.

Original application filed June 21, 1923, Serial No. 646,887, and in Sweden July 3, 1922. Divided and this application filed January 14, 1927. Serial No. 161,223.

This invention relates to an improved plant for sintering fine ores or pulverulent ores.

The object of the invention is to provide a sintering system or plant of the said kind which enables a practically continuous sintering of such ores at low cost and in such way as to secure the most hygienic conditions possible as regards the operators.

10 The invention consists, chiefly, in a sintering system, comprising a plurality of independent portable sintering vessels, exhausting apparatus, a plurality of work positions, suction pipes extending from said exhausting apparatus to all of the work positions and each adapted to be kept connected with one sintering vessel during the sintering of the material contained therein, a track extending along the work positions to a discharge place for the sintered material, transporting means on said track adapted to transport the vessels with the sintered material from either of the work positions to the discharge place, and a charging apparatus at 25 said track at a distance from the work positions.

Due to the fact that the charge filling and emptying operations take place at distant points from the sintering positions the latter will be free from injurious dust and smoke. With the method according to this invention as compared with hitherto known methods a larger output, lower working expenses and a better sintering product will result 35 from the fact that the charge filling and sintering operations may be better supervised when taking place at different places without exposing the operators to injurious smoke and heat and that the sintering vessels rest 40 stationary during the sintering operation proper.

In the accompanying drawings several examples of plants according to this invention are shown. Fig. 1 is a diagrammatic plan view of a plant according to one embodiment of the invention. Fig. 2 is a diagrammatic elevation of said plant. Fig. 3 is an elevation of the charge filling device of said plant. Fig. 4 is an elevation of a tilttable sintering 50 vessel and Fig. 5 is a vertical section of said vessel taken at right angles to the elevation shown in Fig. 4.

Fig. 6 is a diagrammatic elevation, with part in section, of a second form of plant

according to the invention. Fig. 7 is a cross section and Fig. 8 is a plan view of said second plant.

Fig. 9 is a diagrammatic elevation of a third plant. Fig. 10 is a cross section and Fig. 11 is a plan view of said third plant.

The plant shown in Figs. 1-5 comprises a charge filling house 1, an exhausting house 2, a work platform 3 at one side thereof, an emptying place 4 and a cable way 5 extending from the emptying place, through the charge filling, and from thence in two parallel branches over the platform 3 and back to the emptying place. At the emptying place a connection (not shown) is provided between the ends of the cable way so that the latter forms, in fact, a closed circuit. The cable way is adapted to carry sintering vessels from the emptying place 4 to the charge filling house and, after the charge filling operation has been completed, to a work position on the platform 3 where the sintering operation takes place, and after the completion of said sintering operation back again to the emptying place, as will be hereinafter more fully set forth.

The sintering vessels (Figs. 4, 5) comprise tilttable open-topped receptacles 6 having supporting arms 7 by means of which the vessels may be suspended on and moved along the cable way 5. Each sintering vessel is provided with a grate 8 (Fig. 5) to support the charge. The said grate rests on an annular bracket 9 which may be adjusted vertically by any suitable means (not shown). Mounted below the grate 8 is a suction pipe 10 having a downwardly directed mouth. In the bottom of the sintering vessels shutters 12 may be provided to facilitate cleaning of the vessel.

The charge filling house 1, Fig. 1, encloses any appropriate type of mingling apparatus to effect an intimate mixing of the fine ore or pulverulent ore with a sufficient quantity of powdered fuel. In Figs. 2 and 3 the outlines of the mingler are indicated at 13. The mingler is provided at its lower end with two storage pockets 14, Fig. 3, situated at opposite sides of the cable-way 5 so as to permit the vessels to remain suspended on the cable during the charge filling operation. The charge filling operation is carried out by swinging out the bottoms 16, 16 closing the lower ends of the pockets

around their pivots 15, 15, thereby permitting the material contained in the pockets to drop into the sintering vessel and fill same. The bottoms are then swung inwards so as to again close the ends of the pockets, at the same time levelling the surface of the charge in the vessel filled. The mingler 13 is filled by means of any suitable conveying device 13*, Fig. 2.

- 10 The sintering vessel, having been filled, is removed from the charge filling house and carried up to a work position on the platform 3. In the drawing, Fig. 1, two parallel rows of work positions 17, 18, 19, 20 and 21, 15 22, 23, 24, respectively, are shown. The exhausting house encloses an exhauster 26 driven by an electric-motor 25. The suction pipe 27 of the exhauster is connected with two suction chambers 28, 29 each of which is 20 situated below one of the rows of work positions. Extending from said suction chambers to each of the corresponding positions is a pipe 30, 31, respectively. Situated above each position is a fixed igniter 32.
- 25 In the drawing, Fig. 1, the four positions 17, 18, 19, 20 of one row are shown as occupied by sintering vessels. The charge filling operation takes place in the order 17, 18, 19, 20. After the charge within the first 30 charged sintering vessel on 17 has been completely sintered, the said vessel is removed by the cable way and carried up to the emptying place. The vessel having been emptied is moved to the charge filling house, 35 where it is again filled and is then placed on position 21. The next vessel in which the sintering operation is completed is that on 18 and when the sintering in this vessel is completed the vessel is moved in the same 40 way as that described above in connection with the vessel from 17. After the vessel from 18 has been emptied and charged it will be placed on the position 22. This procedure will be repeated till all the positions 45 21, 22, 23, 24 have been occupied. The positions 17, 18, 19, 20 are now idle. When the charge of the vessel on 21 has been completely sintered, said vessel is emptied at 4, again filled at 1 and placed on the position 50 17 and so on.

In the way described a practically continuous operation may be obtained. Moreover, the sintering places will be completely free from the dust inherent to the emptying 55 of the vessels.

In the plant shown in Figs. 6-8 101 is the charge filling place, 102 is the exhausting house, 103 is the work platform and 104 is the emptying place. All of the sintering or 60 work positions are arranged in a single row divided in two groups 105-109 and 110-114, respectively. Each group has a common suction chamber 115 and 116, respectively, in communication with the suction 65 side of the exhausters 117, 118 within the

exhausting house 102. Provided along the row of sintering positions are rails 119 to carry a movable igniter 120, which may be moved over the row of positions 105-114 and the sintering vessels thereon.

Provided along with the row work positions is a rail-way 121 further extending to the emptying place 104. The work positions and the corresponding portion of the railway 121 are enclosed within a house 122 also enclosing a travelling crane 125 serving to lift the sintering vessels. Mounted above the railway 121 outside the house 122 is the charge filling device 101. The charge filling device is not shown in detail, as it 70 may be of the type described above. The feeding of the device 101 may be effected by a belt conveyer 123 or the like.

The operation is as follows:

As soon as the charge in any of the vessels 85 is sufficiently sintered, this vessel is removed from its position by means of the travelling crane 125 and placed on a wagon 124 on the railway 121 by means of which the vessel is carried up to the emptying place 104, 90 where it is emptied. The wagon 124 with the emptied vessel is moved back on the railway 121 and is stopped below the charge filling device 101. The vessel is now filled with a fresh charge and the wagon with the 95 filled vessel is thereupon moved to a position in register with the respective work position. The vessel is then removed from the wagon and placed on its position by means of the crane 125. The igniter is moved up 100 in register with the said vessel and caused to ignite the charge therein. The same procedure is repeated as regards the remaining vessels according as the sintering of their contents is completed. The number of work 105 positions is such as to permit a substantially continuous operation, that is, the sintering of the charge of a subsequent vessel will be ended when the preceding vessel has been charged and the charge therein ignited.

Figs. 9-11 show a small plant based on the same principle that underlies the plant shown in Figs. 6-8.

A number of work or sintering places 205-210 are provided above a common suction chamber 215 communicating with the suction side of the exhauster 217 within the exhausting house 202. Extending along the work positions at a higher level is a railway 219 on which the igniter 220 may move over 115 the vessels situated on said positions, and provided in the extension of the row of work positions is a railway 221 supporting a wagon 224 large enough to enable two sintering vessels to stand thereon at the same time. The work places and a portion of the railway 221 are enclosed within the house 222. This house also enclosed an elevated rail 223 with a travelling crane 225. The rail 223 120 extends to the emptying place 204. Mounted 125 130

above the railway 221 immediately outside the house 222 is the charge filling device 201. The design of said device may substantially correspond to that described in connection with the first embodiment. The material is supplied to the charge filling device from a mingler 200. Provided at the emptying place is a chute 230 having a sieve (not shown) to cause dusty and like particles to drop through the hopper 231 down into a wagon 232 on the railway 233 while allowing the sintered material to slide down into a wagon 234 on another railway 235.

10 The operation is as follows:

15 Let it be assumed that a filled vessel is standing on the wagon 224. When the charge in any of the vessels on the work positions 205—210 has been completely sintered, this vessel is lifted from its work position by means of the crane 225 and carried up to the emptying place 204 where it is emptied. The vessel having been emptied, is carried up by the crane 225 to the wagon 224 and placed thereon, whereupon the 25 charged vessel already standing on the wagon is lifted and placed on the position of the vessel just emptied. The vessel on the wagon 224 is carried up below the charge filling device 201 and again filled with material to be sintered. The wagon with the charged vessel is then moved back again to the position shown in Fig. 11. As soon as sintering 30 is completed in a further vessel, this vessel is subjected to the operation described.

35 What I claim is:—

1. A sintering system, comprising a plu-

rality of independent portable sintering vessels, exhausting apparatus, a plurality of work positions, suction pipes extending from said exhausting apparatus to either of the 40 work positions and each adapted to be kept connected with one sintering vessel during the sintering of the material contained therein, a track extending along the work positions to a distant discharge place for the sintered material, transporting means on said track adapted to transport the vessels with the sintered material from either of the work positions to the discharge place, and a charging apparatus at said track at a distance 45 from the work positions.

2. A sintering system, comprising a plurality of independent portable sintering vessels, exhausting apparatus, a plurality of work positions, suction pipes extending from said exhausting apparatus to any of the work positions and each adapted to be kept connected with one sintering vessel during the sintering of the material contained therein, an igniting device movable along the 50 work positions to either of said work positions, a track extending along the work positions to a distant discharge place for the sintered material, transporting means on said track adapted to transport the vessels with the sintered material from each of the work positions to the discharge place, and a charging apparatus at said track at a distance 55 from the work positions.

In testimony whereof I have signed my 60 name.

ANDERS HOLMBERG.
